US0D1090919S

(12) **United States Design Patent** (10) Patent No.: **US D1,090,919 S**
(45) Date of Patent: **** Aug. 26, 2025**

(54) **REAR COMBINATION LAMP FOR A MOTOR VEHICLE**

(71) Applicants: **TOYOTA JIDOSHA KABUSHIKI KAISHA**, Toyota (JP); **SUBARU CORPORATION**, Tokyo (JP)

(72) Inventor: **Yuki Takamatsu**, Ota (JP)

(73) Assignees: **TOYOTA JIDOSHA KABUSHIKI KAISHA**, Toyota (JP); **SUBARU CORPORATION**, Tokyo (JP)

(**) Term: **15 Years**

(21) Appl. No.: **29/795,488**

(22) Filed: **Jun. 18, 2021**

(30) **Foreign Application Priority Data**

Dec. 25, 2020 (JP) ..... 2020-028246 D
